(57) **CLAIM**

The ornamental design for a surface configuration of a side mirror for a vehicle, as shown and described.

DESCRIPTION

This application is related to co-pending application Ser. No. 29/129,138, of the inventor, filed on even date herewith and entitled “surface configuration of a vehicle and toy”.

FIG. 1 is a perspective view of a surface configuration of a side mirror for a vehicle according to my novel design;

FIG. 2 is a side view of the surface configuration of a side mirror for a vehicle according to my novel design;

FIG. 3 is a front view of the surface configuration of a side mirror for a vehicle according to my novel design; and,

FIG. 4 is a top view of the surface configuration of a side mirror for a vehicle according to my novel design.

The broken lines included depict environment and are not part of the claimed design.
